United States Patent Office

Des. 191,724
Patented Nov. 7, 1961

191,724

TYPEWRITER

David O. Chase, Camillus, and Philip H. Stevens, Syracuse, N.Y., assignors to Smith-Corona Marchant Inc., Syracuse, N.Y., a corporation of New York

Filed Aug. 25, 1960, Ser. No. 60,700

Term of patent 14 years

(Cl. D64—11)

Des. 191,724

PAGE 2

FIG. 2

FIG. 3

FIG. 4

FIGURE 1 is a front perspective view of a typewriter, showing our new design;

FIGURE 2 is a right side elevational view;

FIGURE 3 is a rear elevational view thereof; and

FIGURE 4 is a left side elevational view thereof.

The essential features of our design reside in the portions shown in solid lines on the drawings.

We claim.

The ornamental design for a typewriter, substantially as shown and described.
